CHARLES J. DODGE, OF BROOKLYN, NEW YORK.

SOUND AMPLIFIER FOR PHONOGRAHS AND METHOD OF MAKING THE SAME.

Application filed December 6, 1918. Serial No. 265,496.

To all whom it may concern:

Be it known that I, CHARLES J. DODGE, a citizen of the United States, and a resident of the borough of Brooklyn, city and State of New York, have invented certain new and useful Improvements in Sound Amplifiers for Phonographs and Methods of Making the Same, of which the following is a specification.

10 My invention relates to sound amplifiers for phonographs and the method of making the same. One object of my invention is to simplify the construction of the throat and horn of the phonograph as a matter of 15 facilitating the manufacture of these parts and of making them more uniform. Another object of my invention is to provide a throat and horn of homogeneous construction; that is, a construction in which both 20 of these parts are formed of a single piece of material. I have found that the acoustic qualities of the amplifier are much better where the throat and horn are homogeneous. It is not possible to make these 25 parts from wood and to make them homogeneous whereas, in the present case, these parts may be made homogeneous and at a cost which is less than the cost of making these of wood in separate parts.

30 Another object of my invention is to make the amplifier of a mouldable material in order to simplify the construction thereof and in order to secure the most advantageous shapes without increasing the cost of 35 manufacture. Another object is to make the amplifier of a mouldable composition which when set will have all the tone qualities of wood and in some respects superior thereto. In the present device I am able 40 to obtain the mellow tones usually obtained with wood and to eliminate the irregularities due to the grain of the wood. Where a curved portion of the sound member, such as the throat, is made of wood, the grain 45 is not suitably arranged for all portions thereof, whereas, in the present device, I obtain the quality ordinarily obtained with wood but without having a grain structure, so that the sound waves are more uniformly 50 directed.

My invention also includes a novel core

or form over which my improved amplifier is adapted to be made.

In the drawings forming part of this application,

55 Figure 1 is a side elevation of an amplifier consisting of the throat and horn, embodying my invention, part thereof being broken away for illustrative purposes.

Figure 2 is a sectional view taken on the 60 line 2-2 of Figure 1.

Figure 3 is a sectional view taken on the line 3-3 of Figure 1.

Figure 4 is a vertical sectional view 65 showing the method of making the amplifier on a form or mould,

Figure 5 is a similar view taken in a plane 70 at right angle to the plane on which Figure 4 is taken,

Figure 6 is a perspective view of one of 75 the form members,

Figure 7 is a perspective view of one part of one of the form members,

Figure 8 is a perspective view of another 75 form member,

Figure 9 is an elevation of one portion 80 of the form and

Figure 10 is a plan view showing one 85 method of preparing the material for the form.

The method of making the amplifier consists, partly, in forming a plastic or semi-plastic mass which can be pressed, rolled or cast upon a core or form and which mass when set will be sufficiently firm and hard 90 to form a resonant body. As my invention includes a resonating body made of a new composition of matter I will first describe herein the method of making the material, and the ingredients which form it.

95 The following is the preferred method of making the composition, although to some degree the materials may be altered and some may even be omitted without losing the more important features or characteristics and I state the specific materials and the preferred quantities by way of example. The materials used and the preferred proportions are as follows: $\frac{1}{2}$ pound glue, 2 pounds whiting, $1\frac{1}{2}$ quarts sawdust, $1\frac{1}{2}$ pounds plaster of Paris, $2\frac{1}{2}$ quarts pulp, 1 pint raw linseed oil.

I utilize fibre to strengthen the material and for acoustical reasons I prefer to use wood fibre. A convenient way of preparing this is to reduce paper made of wood pulp to a state of pulp by boiling a quantity of paper with just sufficient water to reduce the whole to a soft mass. This mass is strained or pressed to remove the greater portion of the water.

5 10 The sawdust is prepared by mixing it with the raw linseed oil. The purpose of this is to cause the sawdust to absorb some of the oil so that it will not absorb the plaster when the ingredients are all combined, as 15 that would tend to reduce the acoustical properties of the sawdust.

The whiting is added to the mixture of sawdust and oil and the whole is thoroughly mixed.

20 25 The glue is made off to about the consistency of cabinet maker's glue and one half the quantity is mixed with the mass which comprises the sawdust, oil and whiting. The fibre or wood pulp is also added. The mass thus made is then kneaded like dough. It will not set quickly so that there is ample time for handling the material and working it into the proper condition, which should be as free as possible from bubbles or air 30 holes. When the material is to be used the above mass is prepared by kneading it into the plaster of Paris and the remaining one-half of the glue. The plaster of Paris has a 35 tendency to make the mass set so that this last operation is carried out just before the material is used. The mass thus prepared should have about the consistency of dough or putty. It is preferable to maintain a 40 plastic condition through the various steps in order that the sawdust and fibre will remain evenly distributed throughout the mass.

The mass last described is then rolled out as shown in Figure 10 by passing a roller back and forth over the mass to flatten it out into a body of even thickness and to remove air spaces. The material is then ready to be applied to the form. The sheet of plastic material is then placed around the mould or form and pressed into close contact throughout, the edges of the material being pressed together so that there is no seam. It is preferable, after the material has been applied to the form as shown in 55 Figures 4 and 5 to pass the roller over all portions thereof for the purpose of eliminating air holes and for the purpose of getting the material smooth and of uniform thickness. If desired, the form may be oiled before the material is applied, to prevent the latter from adhering to it. The material is left on the form until it has partly or wholly set and then the form is disassembled and 60 removed.

65 It will be observed that the throat 1 and

the horn 2 are made in one homogeneous body without joints and the density of the whole can be very uniform. This renders the amplifier very satisfactory for phonographs as it is clear in tone. The sawdust and fibre make it possible to amplify the tones with all their quality as these elements have similar characteristic acoustical properties as the fibre construction in wooden amplifiers. At the same time, there is no 70 regular arrangement of these elements corresponding to the grain of natural wood and I consider this an advantage because, where the amplifier comprises a curved portion like the throat 1 a natural grain structure can 75 80 not be advantageously arranged for all portions of the curved body.

By making the amplifier of plastic material it is an easy matter to eliminate objectionable angles and to pass gradually from 85 a round into a substantially rectangular body. In Figures 1, 2 and 3 I have shown an amplifier which has a circular cross section, as shown in Figure 2, from the end 3 of the throat down to about the line 4. The 90 body then gradually tapers into a substantially rectangular formation. As shown in Figure 3, the four sides have a slight curve or swell at 5 and at the meeting lines the body has curves 6 of even thickness. The 95 elimination of sharp corners is better for acoustical purposes but it is difficult or expensive to provide these curves where the amplifier is constructed of wood.

In the drawings I have shown a knock-down form or core on which the amplifier is adapted to be moulded. It comprises, in part, the larger, flared, member 7 which is preferably, though not necessarily, hollow. This member conforms in shape to the interior of the larger, flared end or horn 2 of the amplifier. I have shown it as flared on a long angle along the side 8 with a more straight side 9 opposite, but the angles will be altered according to the shape to be given 105 to the amplifier.

The top of the member 7 preferably extends to a line which is slightly below the axial line of the perpendicular portion 10 of the throat. At the back there is a key 11 115 projecting upwardly from the top 12 and at the front there is a socket 13 extending inwardly from the flattened portion 14. At the bottom the socket 13 has an undercut 15 in which another form member is adapted to 120 lock.

The member 16 which forms the part of the mould, near the inner side of the throat bend is shown in Figure 8. It consists of a block having a projection 17 which is slightly tapering to permit its disengagement and this member fits snugly into the socket 13. This member 17 tapers narrower from front to rear as shown and it tapers narrower from the top toward the bottom, so that it will fit 125 130

the socket 13 tightly as it moves downwardly into position. The bottom 18 of the projection 17 is undercut, so as to enter the undercut bottom 15 of the socket 13 and prevent the member 16 from being displaced forwardly or away from the member 7. The front portion 19 of the member 16 conforms to or is a continuation of the curve of the member 7, in order to constitute a portion of the form proper. The member 16 is shown as having a flat end 20 provided with a key 21 extending forwardly.

The remaining member of the form is the one over which the upright portion of the throat is formed. This member 22, is preferably cylindrical for the greater part of its length and it has its rear end curved at 23 to form a continuation of the curve of the member 7. It also is cut away to a line 20 below the axis, to form a flat portion 24 which is adapted to rest against the tops of the members 16 and 7. This member 22 has a recess 25 at its rear end to receive the key 11 of the member 7 and it has a recess 26 to receive the key 21 of the member 16, the purpose of these keys being to keep the form members in alignment.

When the several form members are assembled, as shown in Figures 4 and 5, their combined contours conform to the shape of the interior of the amplifier, with no projections or shoulders to interlock with the moulding material. I have shown a simple arrangement for holding the form members together while the amplifier is being formed, and which will permit of ready disassembling of the form. There is a bar 27 arranged across the member 22 and one end of a rope 28 is fastened to this bar. The rope passes through the bore 29 of the member 22 through the cutaway 30 of the member 16 and through the interior of the member 7; and its other end is fastened to a cross bar 31 in the member 7. The latter bar is accessible through an opening 32 in the base and the tray. When the rope 28 is tightened and secured in the manner shown it draws the several form members together at their meeting surfaces and holds them firmly in that condition.

The member 7 is preferably attached to a tray 33 having the flange 34 extending around its edge. This flange may serve as a guide to gauge the thickness of the material applied to the form and there is a cap 35 having a flange 36 spaced from the member 22 to gauge the thickness of the material at the upper end of the form.

The form is assembled as shown in Figures 4 and 5 when a cast is to be made. The material is then applied over the whole exterior of the form and then pressed or rolled even and uniform in thickness and the material is then allowed to set while still on the form. The material may remain on the

form until it has completely set and hardened or it may even be removed before it has entirely set but after it has dried out sufficiently to maintain its shape until completely dried. When the material has sufficiently set to permit the removal of the form the rope 28 is released from the bar 31 and the several form members are then no longer held together. The form member 7 may be withdrawn from the larger end 70 of the amplifier, as the parts of the form are so designed that the member 7 will disengage from the members 22, 16 when the member 7 is drawn downwardly or out through the larger end of the amplifier. 80 The form member 22 may now be withdrawn endwise from the tubular portion 10 of the throat and in a direction at right angle to the movement of the larger form member 7. The engagement between the members 22 85 and 16 is such that the former may be withdrawn endwise in the manner described. When both members 22 and 7 have been thus withdrawn, the member 16 which occupied the inner side of the bend of the throat will 90 drop out because there is then nothing to maintain it in position. In this manner the form is disassembled and removed from the amplifier without injuring or distorting the latter and the form is adapted to be used 95 over and over again.

I have found that the shape of the amplifier shown herein is a decided improvement over others having rectangular cross sections and that I obtain clearer and more brilliant 100 reproductions with it. I shall, therefore, claim herein an amplifier having the shape shown and described herein.

Having described my invention, what I claim is:

1. An amplifier for phonographs having a tapering sound chamber and composed of a composition of matter consisting principally of plaster and having wood fibre incorporated in and intimately mixed therewith to 110 form a homogeneous mass.

2. An amplifier for phonographs having a tapering sound chamber and composed of a mouldable composition of matter consisting principally of plaster and having wood 115 fibre and sawdust incorporated in and intimately mixed therewith to form a homogeneous mass.

3. An amplifier for phonographs having a tapering sound chamber and composed of 120 a mouldable composition of matter which includes plaster of Paris, whiting and glue and having wood fibre incorporated in and intimately mixed therewith to form a homogeneous mass.

4. A sound amplifier for phonographs having a tapering sound chamber and composed of a mouldable composition of matter which includes plaster of Paris, whiting, glue and linseed oil and having wood fibre 130

incorporated in and intimately mixed therewith to form a homogeneous mass.

5. A sound amplifier having a tapering sound chamber and composed of a mouldable material including in its composition the following constituents in substantially the following proportions; to wit: glue $\frac{1}{2}$ pound,

whiting 2 pounds, sawdust $1\frac{1}{2}$ quarts, plaster of Paris $1\frac{1}{2}$ pounds, wood fibre $2\frac{1}{2}$ quarts, and linseed oil 1 pint, all intimately mixed to form a homogeneous mass.

Signed at the city, county and State of New York, this 29th day of November, 1918.

CHAS. J. DODGE.
